UNITED STATES PATENT OFFICE.

JOHN MIKULASEK, OF NEWTON, IOWA.

IRONING MACHINE.

1,417,625.

Specification of Letters Patent. Patented May 30, 1922.

Application filed October 27, 1920. Serial No. 419,939.

To all whom it may concern:

Be it known that I, JOHN MIKULASEK, a citizen of the United States, residing at Newton, in the county of Jasper and State of Iowa, have invented new and useful Improvements in Ironing Machines, of which the following is a specification.

This invention relates to ironing machines in which the clothes, fabrics, etc. are ironed by being pressed by a heated shoe against a rotating roller.

The invention has for its object to provide a novel and improved roller mount which renders the same readily accessible for the 15 positioning thereon of the work.

A further object of the invention is to provide a novel and improved driving and controlling means for the roller and the ironing shoe, by which the machine is rendered automatic in operation, the entire control being effected by a foot pedal.

Other objects and advantages of the invention will be pointed out in the detailed description appearing hereinafter, and in 25 order that the invention may be better understood, reference is had to the accompanying drawings forming a part of this specification.

In the drawings, 30 Figure 1 is a plan view of the machine, minus a hood;

Fig. 2 is a front elevation, partly in section;

Fig. 3 is a side elevation, also partly in 35 section;

Fig. 4 is a horizontal section showing a motor and a friction gear;

Fig. 5 is a cross section showing an end 40 view of said motor and gear;

Fig. 6 is a longitudinal section of a work supporting roller;

Fig. 7 is a detail in perspective of certain 45 controlling devices;

Fig. 8 is an elevation of said devices with the work-supporting roller and an ironing shoe shown diagrammatically, and

Fig. 9 is a view similar to Fig. 8 but showing the parts in another position.

Referring specifically to the drawings, 50 10 denotes a roller over which the clothes to be ironed are hung for engagement by a heated pressing shoe 11, the roller being rotatable to feed the clothes between the same and the pressing shoe. A suitable stand supports the ironing mechanism, the same being provided 55 with a base frame 12 equipped with caster

wheels 13 so that the machine may be easily moved about. The stand has upright angle bars 14 at its corners to the upper ends of which is fastened a frame 15, above which 60 latter the elements 10 and 11 are positioned. Over the angle bars 14, from three sides of the machine are fastened sheet metal coverings 16, and in front is a double door 17 swinging on hinges 18. When the machine 65 is not in use, a hood 19 may be placed on the frame 15 to exclude dust from the parts above the latter and to conceal the same. The machine is a portable one, and it is designed so that it may be installed in any 70 convenient room in a dwelling, without detracting from the appearance thereof. The machine is also so designed that it takes up no more space than an ordinary domestic sewing machine, and when constructed in a cabinet type it is a fitting piece of furniture. 75

To the base frame 12 is fastened a housing frame 20 over which is set a housing cover 21 enclosing most of the mechanism and gears. The base frame 12 also supports 80 a housing 22 having a section 23, and provided with top ventilating holes 24, and a bottom slot 25, through which latter a foot lever 26 passes.

The frame 12 and housing 22 have vertically aligned bosses carrying pivot screws 27 supporting a frame 28 carrying an electric or other motor 29 having its shaft fitted with a friction wheel 31 for driving a concave friction disk 32 carried by a shaft 33. The 90 friction wheel 31 engages the concave side of the disk 32, this side being spherical, the center of the curvature lying upon the axis of the pivot screws 27. The friction wheel engages the friction disk edgewise, and its 95 edge having a convex curvature coinciding with the curvature of the concave friction surface of the disk. In order to take up the end thrust, a ball bearing 34 is interposed between the friction wheel and the bearing 100 on the motor frame for the motor shaft.

The motor 29 is fastened at its base to an arm 35 pivoted, as shown at 36 to the frame 28. Against the arm 35 bears one end of a spring 37 having its other end seating 105 against a rib 38 on the frame 28. At the top, the motor 29 is supported by a pivot screw 39 carried by the frame 28. The pivots 36 and 39 are in vertical alignment, and parallel to but offset laterally with respect 110 to the pivots 27.

Referring to Figs. 2, 4 and 5, it will be

- seen that the spring 37 tends to turn the motor 29 in a counter-clockwise direction, whereby the friction wheel 31 is held pressed against the friction disk 32, insuring thereby by a steady and even driving contact even if the center of the spherical surface of the disk does not coincide exactly with the pivots 27, or if said surface should wear in one place more than in another.
- 10 The foot lever 26 is connected to the frame 28 for swinging the latter about its pivots 27. This motion of the frame 28 shifts the friction wheel 31 to and from the center of the disk 32, whereby the speed at which the latter is driven is varied.
- In order to lock the frame 28, the foot lever 26 carries a latch pin 40 engageable with a notched sector 41 on the frame 12.
- The housing enclosing the motor and the friction gear, is made in two sections 22 and 23, the former being stationary and carrying the top pivot screw 27. The section 23 is detachably fastened to the base frame 12 for inspection of the mechanism.
- 20 As the center of the curved friction surface of the disk 32 lies upon the axis 27 of the frame 28, it will be seen that the friction wheel 31 remains in driving contact with the friction disk when the frame is shifted to vary the speed of the friction disk, and as the axis of the friction disk and the friction wheel are parallel, and the latter is edgewise in driving contact with the former, the arrangement produces a wide surface of contact, and the contacting surfaces move with the same relative speed at all points. This is not the case with an ordinary friction drive where the axes of the driver and the driven friction members 30 are at right angles to each other. In this case, if the driver is a friction wheel engaging with its edge the face of a friction disk, the surface speed of the contacting surfaces nearest the axis of the disk is less than at 35 points farther from said axis.
- The shaft 33 driven by the friction gearing hereinbefore described, operates the roller 10 and the shoe 11 through certain instrumentalities to be presently described.
- 40 The frame 15 is provided on its under side with a hub 42 through which extends a tubing 43 rising from the frame and also depending from the hub, with its lower end supported by the housing cover 21. The tubing 43 is fastened to the hub by a set screw 44. Over the upper projecting end of the tubing is fitted and secured by set screws 45, the neck 46 of a hollow bracket member 47, said bracket neck being also bolted to the 45 frame 15. The bracket has a vertical bearing 48 supporting the upper end of a vertical shaft 49, on which shaft is mounted a bevel gear 50 which is in mesh with a bevel gear 51 on a horizontal shaft 52. The shaft 52 is supported in bearings 53 on the inside of a hollow tapered axle 54 fastened to the bracket 47 by a bolt 54a.
- The roller 10 is supported at one end by the inner end of the axle 54 through a ball-bearing 55, and at its opposite end, the roller 70 projects a short distance beyond the corresponding end of the axle and has a hub 56 into which the shaft 52 extends, the hub being pinned or otherwise made fast to the shaft. It will therefore be seen that the 75 roller 10 rotates when the shaft 52 is in motion, said shaft being driven from the shaft 49 through the bevel gears 50 and 51.
- The roller 10 is covered with a layer of soft absorbent material as usual and it is 80 perforated, as shown at 57, through which the absorbed dampness in the cover passes into the roller so as to escape from the outer end thereof, said end being open except for the spokes 58 joining the hub 56 to the roller. 85
- The bracket member 47 at the inner end of the roller 10 does not rise above the latter, and as the opposite end of the roller is also free and unobstructed, it will be evident that a piece of material wider than the roller can 90 be placed thereon without meeting obstructions at the ends thereof. Thus, a wide piece of material can be operated on without being folded, it being simply ironed in strips successively until the whole width is ironed; 95 but if desired, the material can be folded, doubled, or creased, etc. and ironed this way.
- The pressing or ironing shoe 11 has a concave work-engaging face 59 to conform to the peripheral contour of the roller 10. 100 A rear wall 60, end walls 61 and a flat top 62 complete the shoe structure, the same being hollow to house a gas burner or any other suitable heating element 63. The fumes escape through openings 64, in the 105 top 62, at the ends thereof, and air is admitted through a slot 65 at the bottom of the rear wall 60. In the shoe is located a deflector 66 to direct the heat to the work-engaging surface 59 or to the top 62, or both. 110 The top 62 is flat so that a sad-iron I may be heated by being seated thereon as shown in Fig. 3. This provides a convenient means for heating a sad-iron to be used for ironing garments and other articles or parts of such 115 which cannot be handled by the machine.
- On the frame 15 is pivoted, as shown at 67 a frame 68 having operating connections with the shoe 11 to swing the same toward and from the roller 10. To the upper end 120 of the frame 68, is pivoted as shown at 69 a hand release lever 70 which latter is connected by a link 71 with the shoe 11. The frame 68 is also connected to the shoe 11 by a link 72, the connection being made below 125 the link 71. It will therefore be seen that the shoe 11 is carried toward or from the roller 10 when the frame 68 is swung, and the shoe may also be swung by operating the lever 70, the link 72 now functioning as 130

a swinging support for the shoe, the frame 68 remaining stationary. When the frame 68 is swung the lever 70 and the links 71 and 72 swing bodily therewith to carry the shoe 11 toward or from the roller 10. It will be understood that a link connection 72 is made at each end of the shoe 11.

Beneath the frame 15 is a horizontally positioned lever arm 73 which is connected to the frame 68 for swinging the same for the purpose hereinbefore described. The lever arm 73 obtains motion from the shaft 33 through a gearing and other elements to be presently described, and this shaft also drives the shaft 49 which is geared to the shaft 52 for driving the roller 10.

The housing 20 has a step bearing 74 for the lower end of the shaft 49, and on said shaft is loosely mounted a worm wheel 75 which is in mesh with a worm 76 on the shaft 33. On the shaft 49, above the worm wheel 75 is also loosely mounted a bevel gear 77 which is in mesh with a bevel gear 78 having its shaft 79 supported in bearings 20 on the housing cover 21. On the shaft 79 is an eccentric 80 having its strap 81 provided with a rod 82 having a yielding connection with a yoke 83, which latter is connected to the lever arm 73. The yielding connection between the rod 82 and the yoke 83 is made by a spring 84 coiled around the rod inside the yoke between the bottom portion thereof and an abutment 85 on the upper end of the rod, said abutment being 35 a nut so that the tension of the spring may be adjusted. The yoke 83 of course seats slidably on the rod 82. The motion of the eccentric 80, through its connections with the lever arm 73 swings the same to rock the frame 68, whereby the shoe 11 is carried toward and from the work on the roller 10.

The gear 77, through the gear 78 drives the eccentric 80, and the worm wheel 75 drives the shaft 49. As stated hereinbefore, the gear 77 and the worm wheel 75 are loose 45 on the shaft 49, and hence a driving connection must be provided, which will now be described.

Between the worm wheel 75 and the gear 50 77, there is made fast on the shaft by a set screw or other means 86, the hub 87 of a radial arm 88 having at its outer end an abutment in the form of an upstanding roller 89. On the upper face of the worm wheel 75 is a similar abutment 90. On the under side of the arm 88 is pivoted, as shown at 91, a dog 92, and on the under side of the gear 77 is pivoted, as shown at 93, a dog 94. The dog 92 has a depending flange 92^a which 55 is in the path of the abutment 90. The arm 88 has an abutment 95 against which the dog 92 is held pressed by a spring 95^a, and on the gear 77 is an abutment 94^a for dog 94. The parts are so arranged that the shaft 49 is 60 rotated when the worm wheel 75 is in motion

and its abutment 90 is pressing against the flange 92^a of dog 92, and as said dog is carried by the arm 88 and the latter is fast on shaft 49, a driving connection between the dog 92 and the arm 88 is established by the 70 engagement of the dog with the abutment 95 on said arm.

A driving connection between the arm 88 and the gear 77 is established by the engagement of the abutment 89 on said arm 75 with a depending flange 96 on the dog 94 carried by said gear, said flange being in the path of this abutment, and the dog being pressed against the abutment 94^a.

At 97 and 98 are shown trip fingers for 80 the dogs 92 and 94, said fingers extending laterally from rocker arms 97^a and 98^a, respectively, on a rocker bar 99 supported by bearing screws 01 carried by the frame 20. The outer end of the arm 98^a is connected 85 by a rod 02 to a foot pedal 03 supported by the base frame 12. A spring 04 normally holds the pedal 03 elevated, and with the pedal in this position, the trip finger 97 is in the path of the dog 92, whereas trip finger 90 98 is above and out of the path of the dog 94 as shown in Fig. 8. The side arms of the pedal extend through an opening 05 in the base frame 12, and the top of the openings limit the upward swing of the pedal. It will 95 also be noted that the eccentric 80 is positioned directly above the arm 98^a so that it presses down on said arm on its downward stroke. On the upward stroke of the eccentric, the shoe 11, through its connections with 100 the eccentric, is swung away from the roller 10 as shown in Fig. 8, and as the eccentric goes down, the shoe is lowered as shown in Fig. 9. The connections between the eccentric and the shoe are shown diagrammatically only in Figs. 8 and 9.

The operation of the mechanism may be summarized as follows:

Fig. 8 shows the parts when the machine is not running. To start the machine, the 110 motor 29 is started to set the worm wheel 75 in motion. The pedal 03 is now pressed down, which lowers the finger 97 out of the path of dog 92 so that when the abutment 90 reaches the flange 92^a of said dog, the 115 arm 88 is locked to worm wheel 75 and the motion of the latter is transmitted by the arm to shaft 49 to rotate the roller 10. The pedal is depressed far enough to bring the finger 98 below and out of the path of dog 120 94, and hence when the now swinging arm 88 takes its abutment 89 in contact with the flange 96 of dog 94, the gear 77 also starts to turn, and through the gear 78, motion is 125 transmitted to the eccentric 80 to lower the shoe 11 to operative position, this movement of the eccentric being downward. The pedal 03 is depressed only long enough for the abutment 89 to reach the flange 96 of dog 130 94, because when the eccentric 80 goes down

it presses down on the arm 98^a to again place the finger 98 in the path of the dog 94. The eccentric arrives at its lowered position after one half revolution of the arm 88, at the end 5 of which the dog 94 is tripped by the finger 98 so that the motion of the gear 77 is discontinued and the eccentric 80 remains in lowered position, in which position the shoe 11 is down in operative position holding the 10 material to be pressed against the roller 10. The lowering of the arm 98^a by the eccentric 80 also operates to maintain the position of the finger 97 out of the path of the dog 92, and hence the worm wheel 75 remains coupled to the arm 88 and the shaft 49 continues to turn to operate the roller 10. The 15 parts remain in this position until the piece of fabric being ironed is finished, whereupon, the shoe 11 must be elevated and the 20 roller 10 stopped for the insertion of another piece of fabric. This stoppage of the mechanism is effected by again depressing the pedal 03 far enough to take the finger 98 below the position it is held by the eccentric, 25 as shown in Fig. 9, and hence out of the path of the dog 94, so that when the abutment 89 again reaches the flange 96, and gear 77 starts to turn, the eccentric 80 rises to elevate the shoe 11. The pedal 03 is depressed only 30 momentarily, and then released to let the finger 97 come to tripping position, and by the time the shoe 11 has been elevated, the dog 92 has reached the finger 97 and the dog is now tripped to break the driving connection 35 for the shaft 49, so that the roller 10 now also stops.

The bracket member 47 carries a table bracket 06, a pivotal connection being provided, the same consisting of pivot screws 40 07 which enter the ends of the bolt 54^a and provide a hinge connection to enable the table bracket to be dropped down, and it is held in horizontal position by a latch pin 08 adapted to be inserted into a keeper aperture 45 in the bracket member 47. On one side of the table bracket 06 is hinged, by links 09, a feed table 010, and on the other side is similarly hinged a leaf 011 having the shape 50 of an ordinary ironing board, so that it may be used for finishing parts of work which are not reached in the passage of the same between the roller 10 and the shoe 11. The ironing board can also be used for ironing small pieces. The feed table 010 is held horizontal by a set screw 012 and the ironing board is held up by a prop 013. When the 55 machine is not in use, the parts 06, 010 and 011 can be folded as shown dotted in Fig. 3, and covered by the hood 19, which latter 60 keeps everything free from dust, and also disguises the appearance of the machine. For the sake of economy in construction, the machine may be built without the outside mantle 16 and the hood 19, as it still 65 mains a safe and well-housed construction.

The sheet metal cover plates 16 at the ends of the frame are hinged at the top as shown at 16^a, so that they may be swung up into horizontal position, as shown dotted in Fig. 2, in which position they may be held by swinging the doors 17 outwardly beneath the same. This arrangement gives the machine a lower table on which wide pieces 70 passing through the machine may fall.

I claim:

1. In an ironing machine, a work-supporting roller, a shoe for pressing the work against the roller, a pivoted frame, a hand lever pivoted to the frame, a link connection between the hand lever and the 80 shoe, a link connection between the frame and the shoe below the first mentioned connection, and means for actuating the frame to swing the shoe toward and from the roller.

2. In an ironing machine, a work supporting roller, a shoe for pressing the work against the roller, a pivoted frame, a hand lever pivoted to the frame, a link connection between the hand lever and the shoe, a link connection between the frame and the shoe below the first mentioned connection, a lever arm on the frame, and actuating means for the lever arm to swing the shoe toward and from the roller.

3. In an ironing machine, a rotatable work-supporting roller, a shaft having a driving connection with said roller, a driven rotatable actuating member for the shaft loosely mounted thereon, an arm carried by 100 the shaft and fast thereon, a pivoted dog carried by the arm, an abutment on the actuating member into the path of which the dog extends, a shoe for pressing the work against the roller, a swinging supporting 105 member for the shoe operable to move the shoe into and out of operative position, actuating means for said supporting member, said actuating means including a rotatable member loose on the aforesaid shaft, a pivoted dog carried by said rotatable member, an abutment on the aforesaid arm into the path of which the last-mentioned dog extends, and means for tripping the dogs clear 110 of the abutments.

4. In an ironing machine, a rotatable work-supporting roller, a shaft having a driving connection with said roller, a driven rotatable actuating member for the shaft loosely mounted thereon, an arm carried by 120 the shaft and fast thereon, a pivoted dog carried by the arm, an abutment on the actuating member into the path of which the dog extends, a shoe for pressing the work against the roller, a swinging supporting 125 member for the shoe operable to move the shoe into and out of operative position, actuating means for said supporting member, said actuating means including a rotatable member loose on the aforesaid shaft, a 130

5. In an ironing machine, a rotatable member, an abutment on the aforesaid arm into the path of which the last-mentioned dog extends, means for tripping the first-mentioned dog clear of the corresponding abutment, and a tripping means for the last-mentioned dog operable without affecting the first-mentioned tripping means.
5. In an ironing machine, a rotatable work-supporting roller, a shaft having a driving connection with said roller, a driven rotatable actuating member for the shaft loosely mounted thereon, an arm carried by the shaft and fast thereon, a pivoted dog carried by the arm, an abutment on the actuating member into the path of which the dog extends, a shoe for pressing the work against the roller, a swinging supporting member for the shoe operable to move the shoe into and out of operative position, actuating means for said supporting member, said actuating means including a rotatable member loose on the aforesaid shaft, a pivoted dog carried by said rotatable member, an abutment on the aforesaid arm into the path of which the last-mentioned dog extends, tripping fingers adapted to be projected into the path of the dogs for placing the same clear of the abutments, a pivoted support for the fingers operable to trip the second-mentioned dog without affecting the first-mentioned dog, and controlling means for said support.
6. In an ironing machine, a rotatable work-supporting roller, a shaft having a driving connection with said roller, a driven rotatable actuating member for the shaft loosely mounted thereon, an arm carried by the shaft and fast thereon, a pivoted dog carried by the arm, an abutment on the actuating member into the path of which the dog extends, a shoe for pressing the work against the roller, a swinging supporting member for the shoe operable to move the shoe into and out of operative position, actuating means for said supporting member, said actuating means including a rotatable member loose on the aforesaid shaft, a pivoted dog carried by said rotatable member, an abutment on the aforesaid arm into the path of which the last-mentioned dog extends, tripping fingers adapted to be projected into the path of the dogs for placing the same clear of the abutments, a pivoted support for the fingers, and an eccentric engageable with the support of the trip fingers for holding said support in a position in which the tripping of the second-mentioned dog is effected, said eccentric being driven by the aforesaid rotatable member and being interposed in the actuating means of the supporting member of the shoe, and a manual control for the support of the trip fingers.
8. In an ironing machine, a rotatable work-supporting roller, a shoe for pressing the work against the roller, a swinging support carrying the shoe and operable to place the same into and out of operative position, a drive shaft having operative connections with the roller and the shoe, and means for breaking the operative connection between the shaft and the shoe without breaking the operative connection between said shaft and the roller.
9. In an ironing machine, a rotatable work-supporting roller, a shoe for pressing the work against the roller, a swinging support carrying the shoe and operable to place the same into and out of operative position, a drive shaft having operative connections with the roller and the shoe, and means for automatically breaking the operative connection between the shaft and the shoe when the latter has been placed in operative position.
10. In an ironing machine, a rotatable work-supporting roller, a shaft having a driving connection with said roller, a driven rotatable actuating member for the shaft loosely mounted thereon, an arm carried by the shaft and fast thereon, a pivoted dog carried by the arm, an abutment on the actuating member into the path of which the dog extends, a shoe for pressing the work against the roller, a swinging supporting member for the shoe operable to move the shoe into and out of operative position, an eccentric having an actuating connection with said supporting member, a driving member for the eccentric loose on the aforesaid shaft, a pivoted dog carried by said driving member, an abutment on the aforesaid arm into the path of which the last-mentioned dog extends, tripping fingers adapted to be projected into the path of the dogs for placing the same clear of the abutments, a pivoted support for the fingers, and an eccentric engageable with the support of the trip fingers for holding said support in a position in which the tripping of the second-mentioned dog is effected, said eccentric being driven by the aforesaid rotatable member and being interposed in the actuating means of the supporting member of the shoe.
7. In an ironing machine, a rotatable work-supporting roller, a shaft having a driving connection with said roller, a driven rotatable actuating member for the shaft

path of which the last mentioned dog extends, and means for tripping the dogs clear of the abutments.

11. In an ironing machine, a rotatable work-supporting roller, a shaft having a driving connection with said roller, a driven rotatable actuating member for the shaft loosely mounted thereon, an arm carried by the shaft and fast thereon, a pivoted dog carried by the arm, an abutment on the actuating member into the path of which the dog extends, a shoe for pressing the work against the roller, a swinging supporting member for the shoe operable to move the shoe into and out of operative position, an eccentric having an actuating connection with said supporting member, a driving member for the eccentric loose on the aforesaid shaft, a pivoted dog carried by said driving member, an abutment on the aforesaid arm into the path of which the last mentioned dog extends, tripping fingers adapted to be projected into the path of the dogs for placing the same clear of the abutments, and a piv-

oted support for the fingers engageable by 25 the eccentric when the shoe is in operative position to hold said support in a position in which the tripping of the second mentioned dog is effected.

12. In an ironing machine, a portable base, 30 frame, side walls for the frame, said side walls being hinged at the top for extension into horizontal position, front and rear walls for the frame, the front wall being composed of hinged sections, a power plant 35 supported by the base frame, an ironing mechanism, and a support for said mechanism carried by the base frame above the power plant.

13. In an ironing machine, a work-supporting means, a supporting frame for said means, a table bracket pivotally supported by the frame to fold downwardly, a feed table for the work supporting means hinged to the table bracket, and means for holding 45 the feed table in operative position.

In testimony whereof I affix my signature.
JOHN MIKULASEK.
